SOFT FOLD-COLLAR.

1,073,132.

Specification of Letters Patent. Patented Sept. 16, 1913.

Application filed August 2, 1912. Serial No. 712,871.

To all whom it may concern:

Be it known that I, HUBBARD F. HURD, a citizen of the United States, residing at Troy, county of Rensselaer, and State of New York, have invented certain new and useful Improvements in Soft Fold-Collars, of which the following is a specification.

The invention relates to such improvements, and consists of the novel construction hereinafter described and subsequently claimed.

Reference may be had to the accompanying drawings, and the reference characters marked thereon, which form a part of this specification. Similar characters refer to similar parts in the several figures therein.

Figure 1 of the drawings is a view in perspective of a soft fold-collar folded in the form in which said collars are ordinarily worn. Fig. 2 is a similar view showing the collar folded in reversed form. Fig. 3 is a vertical section taken through the band and one of the reversible buttons attached to the band. Fig. 4 is a plan view of the collar laid out flat before the same is folded. Fig. 5 is a similar view showing the collar inverted.

The invention relates to soft fold-collars, that is, collars which are laundered without starch. Such collars are ordinarily made with a band having a long end adapted to be inserted in the fold between the band and folded-over top at the other end of the collar.

In addition to the ordinary means for detachably securing the band of the collar to the neckband of a shirt, it has been found desirable to provide the long projecting end of the band with a buttonhole near its upper edge a short distance outside of the folded-over top at that end of the collar, and to attach to the outer side of the short end of the band just within the fold at the other end of the collar, a button adapted to engage said buttonhole to retain the long end of the band in position. It has also been found desirable in such collars to provide each of the ends of the folded-over top with a buttonhole and to attach to the long end of the band two buttons, adapted to engage the buttonholes in the respective ends of the collar-top when the collar is in use. As heretofore made, such fold-collars could be worn in one folded form only; namely, that in which said buttons appeared upon the

outer side of the band, for the reason that if the collars were folded in reversed form, said buttons would appear upon the inner side of the band making it impossible for said buttons to engage the respective buttonholes and bringing the button attached to the short end of the band into contact with the neck of the wearer.

The principal objects of the present invention are to adapt such a collar for reversal and to properly support the long end of the band in the fold between the band and top at the other end of the collar and to properly support the ends of the folded-over top in connection with the long end of the band in whichever form the collar may be folded. This I am able to accomplish by providing the band at the points where such buttons are to be located with buttonholes and attaching the several buttons to the band adjacent to one of said buttonholes through which buttonhole said button is adapted to be projected from one side to the other of the band.

Referring to the drawings wherein the invention is shown in preferred form, 1, is the band having the short end, 2, and the long end, 3; and, 4, is the top of the collar. The band is provided with the usual back buttonhole, 5, and the front buttonhole, 6, in its short end, and, 7, in its long end, adapted to receive collar-buttons or studs in the usual manner for attaching the collar to the neckband of a shirt. The long end of the band is also provided with a buttonhole, 8, just outside the neighboring end of the folded-over top; and the other end of the band is provided with a buttonhole, 9, just inside the neighboring end of the folded-over top; and a button, 10, is attached to the band adjacent to the edge of said buttonhole, 9, and in position to be-projected back and forth through said buttonhole from one side to the other of the band. The buttonhole, 9, and the button, 10, are so located that the button is adapted to engage the buttonhole, 8, in the long end of the band when said long end is properly inserted within the fold between the top and the band at the other end of the collar.

In Fig. 3, the button, 10, is shown in full lines on one side of the band, and its reversed position on the opposite side of the band is indicated by dotted lines.

Reversing the collar from the form shown

in Fig. 1, to that shown in Fig. 2, brings the button, 10, upon the inner side of the band next to the neck of the wearer; but the buttonhole, 9, permits the button, 10, to be then reversed by projecting it through the buttonhole, 9, from the inner to the outer side of the band.

The stitches whereby the button, 10, is attached to the band may be made to embrace the edge of the buttonhole or may be inserted through the band sufficiently close to the edge of the buttonhole, to permit the reversal of the button.

I prefer to employ a two-eyed button and 15 to have the stitches embrace the edge of the buttonhole, which can be readily accomplished by having the needle pass alternately through one of the eyes of the button and the band adjacent to the buttonhole, 20 and then through the other eye of the button and the buttonhole opening. I have also shown the top provided in each end with a buttonhole, 12, and the band provided in its long end with a pair of buttonholes, 13 and 25 14, so located as to lie opposite the respective buttonholes in the top when the collar is folded and its ends brought together as in use; and I attach to the band adjacent to

the respective buttonholes, 13 and 14, buttons, 15, adapted to be projected through 30 the respective buttonholes, 13 and 14, from one side to the other of the band and adapted to engage the respective buttonholes, 12, in the top in whichever form the collar may be folded.

The buttons, 15, are preferably attached in the same manner as the button 10.

What I claim as new and desire to secure by Letters Patent is—

A soft fold-collar having a band and a 40 folded-over top, said top being provided in each of its ends with a buttonhole, said band having a long end provided with two buttonholes and having buttons attached adjacent to the respective buttonholes 45 adapted to be projected therethrough from one side to the other of the band and to engage the respective buttonholes in the top in whichever form the collar may be folded.

In testimony whereof, I have hereunto set 50 my hand this 31st day of July, 1912.

HUBBARD F. HURD.
